CHARLES A. MASAITIS, OF LINCOLN, NEW HAMPSHIRE, ASSIGNOR OF ONE-FOURTH
TO JOSEPH C. SINKIEWICZ, OF LINCOLN, NEW HAMPSHIRE.

SAFETY-POCKET.

1,370,032.

Specification of Letters Patent.

Patented Mar. 1, 1921.

Application filed March 27, 1920. Serial No. 369,203.

To all whom it may concern:

Be it known that I, CHARLES A. MASAITIS, a citizen of Lithuania, residing at Lincoln, county of Grafton, and State of New Hampshire, have invented certain new and useful 5 Improvements in Safety-Pockets, of which the following is a specification.

This invention relates to the construction of the pockets in trousers, coats or the like 10 and it has for a general object to provide a pocket which will be proof against picking.

A further object is to provide a pocket with an inner or supplementary pocket the 15 entrance to which will be closed when the supplementary pocket is positioned inside the main pocket.

For further comprehension of the invention, and of the objects and advantages 20 thereof, reference will be had to the following description and accompanying drawings, and to the appended claims in which the various novel features of the invention are more clearly set forth.

25 Figure 1 of the drawings is a perspective view of a pair of trousers having the invention embodied in the pockets thereof.

Fig. 2 is a fragmentary perspective view showing the pocket with the supplementary 30 pocket inside.

Fig. 3 is a similar view with the supplementary pocket turned out.

Fig. 4 is a side view of the pocket as shown in Fig. 3.

35 Fig. 5 is a detail section through the pocket.

In the drawings the waist portion of a pair of trousers is shown at 10, the legs being indicated at 11, the usual or any desired number of pockets being provided.

40 Each pocket comprises a main pocket 13 which is constructed as usual with an entrance opening 14 adapted to be covered by a flap 15 in which is a button-hole 16.

Secured inside the main pocket just below 45 the entrance 14 is the supplementary pocket which has the top edge of its inner wall 18 stitched to the material, as at 18' (Fig. 2) just below the entrance opening or mouth. The outer wall 19 of this supplementary 50 pocket is of slightly less height than the inner wall so as to be accommodated beneath the stitched top edge of the inner wall 18 and it will be obvious that the entrance or

mouth of this inner pocket will be closed by the top edge of its inner wall and that 55 access to such inner pocket while the latter is in position in the main pocket will be impossible.

To keep the pockets closed a button 20 is preferably sewed on the inner wall 18 of the 60 supplementary pocket and passed through registering button-holes 21 in the outer wall of the pocket and in the cloth of the trousers, this button also being adapted to have the flap 15 buttoned thereover. 65

As will be apparent rolls of bills or the like can be carried in the supplementary pocket without danger of removal by pickpockets while to remove the contents of this pocket it is only necessary to pull it out 70 through the entrance or mouth of the main pocket to the position shown in Fig. 4, which leaves the mouth of the supplementary pocket exposed.

Having thus described my invention what 75 I claim as new and desire to secure by Letters Patent of the United States is as follows:

1. In a garment, a main pocket, and a supplementary pocket in said main pocket and 80 having the inner wall thereof attached independently of the outer wall to the outer wall of the main pocket near the mouth of the latter thereby concealing the mouth of the supplementary pocket, and a button attached to said inner wall of the supplementary pocket, the outer walls of said main and supplementary pockets having buttonholes formed therein to receive said button. 85

2. In a garment, a main pocket, a supplementary pocket, in said main pocket, said supplementary pocket having its inner wall extended upwardly beyond the outer wall and having such upwardly projecting portion attached to the outer wall of the main 90 pocket just below the mouth of the latter, a flap for covering the mouth of the main pocket, and a button attached to the inner wall of said supplementary pocket and passing through buttonholes in the outer walls 100 of the main and supplementary pockets, and adapted to have the said flap buttoned thereto.

In testimony whereof I have affixed my signature.

CHARLES A. MASAITIS.
